UNITED STATES PATENT OFFICE.

CHARLES D. McDONALD, OF CHICAGO, ILLINOIS, ASSIGNOR TO McDONALD MACHINE CO., OF CHICAGO, ILLINOIS, A CORPORATION OF ILLINOIS.

CAN-TESTING MACHINE.

Application filed June 6, 1927. Serial No. 196,935.

This invention relates to can testing machines, and its principal object is to provide a pneumatic or compressed air can testing machine of novel construction, capable of operating upon a maximum number of cans in a minimum amount of time and occupying a comparatively small floor space, and capable of operating with great certainty, delicacy and accuracy in automatically testing or separating imperfect or leaky cans from hermetically tight or perfect ones. Another object is to provide improved means for automatically admitting compressed air to the cans after they have been delivered to the machine and thereafter sealing the cans, against the escape of the compressed air while the cans are being carried to the selecting mechanism, and thereafter establishing communication between the interior of the cans and a pneumatically operated selector which controls mechanism for separating the imperfect or leaky cans from the hermetically tight or perfect ones.

With these and other objects and advantages in view, this invention consists in a can testing machine embodying a movable carrier equipped with a plurality of compressed air balancing tanks, one for each can or pair of cans, and associated sealing heads and can clamps for clamping the cans against the heads, in combination with compressed air conduits and valve mechanism for admitting compressed air to the cans and associated compressed air balancing tanks and trapping the air therein at the receiving end of the machine, and a pneumatically operated selector or a pair of selectors at the discharge end of the machine which are operated by an unbalanced pressure in any compressed air balancing tank and an associated can which is clamped on its associated head. It further consists in a machine as set forth in which each selector operates to control mechanism for separating the selected cans from the rejected ones. It further consists in automatic means for controlling the action of the pneumatic mechanism, the selector and the can separating mechanism. It further consists in the several novel features of construction, arrangement and combination of parts hereinafter fully set forth and claimed.

The invention is clearly illustrated in the drawings accompanying this specification, in which:

Fig. 1 is a side elevation of a can testing machine embodying a simple form of the present invention and showing the can carrier stripped of much of its equipment for the purpose of simplifying the view; Fig. 2 is a vertical cross section taken on the line 2—2 of Fig. 1; Fig. 3 is a detail section taken on the line 3—3 of Figs. 1 and 4 and showing two cans secured in place on one of the can holding heads of the machine; Fig. 4 is a fragmental view in side elevation of the parts seen in Fig. 3, with certain portions broken out to illustrate parts that would otherwise be hidden from view; Fig. 5 is a detail side elevation of the can separating mechanism; Fig. 6 is a plan of the parts seen in Fig. 5; Fig. 7 is an enlarged side elevation of one of the selectors which forms part of the present invention, the glass cover thereof being removed; Fig. 8 is a detail vertical cross section taken on the line 8—8 of Fig. 7; Fig. 9 is a rear elevation of the selector seen in Figs. 7 and 8 with its supporting plate removed; Fig. 10 is a detail cross section of the selector taken on the line 10—10 of Fig. 9; Fig. 11 is a detail plan of a certain link connection which forms part of the selector mechanism; Fig. 12 is a detail cross section taken on the line 12—12 of Fig. 9; Fig. 13 is a detail vertical cross section of an air valve device, the line of section being indicated at 13—13 of Fig. 2; Fig. 14 is a detail horizontal section taken on line 14—14 of Fig. 13; Fig. 15 is a detail view, partly in plan and partly in section, of the selectors and certain air controlling means, the line of section being indicated at 15—15 in Fig. 1; Fig. 16 is a detail front elevation of a certain track or guide way for operating the can clamps; Fig. 17 is a side elevation of the parts seen in Fig. 16; Fig. 18 is a detail view, partly in side elevation and partly in vertical section of certain valve actuating mechanism for the air valve device, the line of section being indicated at 18—18 of Fig. 1, and Fig. 19 is an elevation of the clamping mechanism of one of the can clamping heads.

Referring to said drawings, which illustrate a simple embodiment of the invention,

and first to Figs. 1 and 2, a base 20 is provided, upon which is mounted the body or standard 21 of the machine, the upper end of which is formed with bearing boxes 22 in which is rotatively mounted the carrier head 26 that carries the cans through the machine. The carrier head has a hub 26^a and a hollow shaft 23 which are journaled in said bearing boxes, and the head is rotated by any suitable mechanical means, as for instance a worm gear 24 mounted on the hollow shaft 23 and meshing with a worm pinion 25, driven from any suitable source of power.

15 As illustrated, the carrier head is provided with a multiplicity of circumferentially arranged can clamping heads 27 and each can clamping head is formed with two can clamping members (see Fig. 3) whereby 20 two cans may be carried by the same head. Each head is formed with a clamping plate or abutment member 28 against which the two cans are clamped, one on each side thereof, and a pad 29 is secured upon one 25 side of the plate 28 for engagement with the open end of one can. The clamping plate 28 projects from a boss 30 formed as a separate part of, or as an integral part of the carrier head 26. Slidably mounted on 30 a spindle 31, secured in the boss 30, are clamping arms 32, 33, on which are secured can clamping discs 34, 35, which discs are preferably provided with stems 36, 37, adjustably secured in the arms 32, 33 for the 35 purpose of adjustment for long and short cans. The disc 34 may be made solid for engagement with the closed end of a can, whereas the disc 35 is provided with a resilient clamping pad 29^a for engagement 40 with the open end of the can and making a tight fit thereon, and the stem 37 is made hollow and opens out through the outer face of the pad 29^a, whereby compressed air may be supplied to the interior of the 45 can clamped thereon and from said opening leads a conduit which runs to an air valve as will be described hereinafter. Links 38, 39 are connected to the disc supporting arms 32, 33 and the free ends of said 50 links are connected to a lever 40 which is provided with an arm 41 on which is mounted a roller 42 that engages with a track or grooved guide way 43, (see Figs. 16, 17) mounted on some stationary portion 55 of the machine as for instance the base 20. A can carrier 28^a (see Figs. 3 and 4) is secured to each can clamping head and has a concave seat for receiving the can as it is delivered to the can clamping head from the delivery chute, and said can carrier operates to locate the can in position to be clamped in place by the clamping mechanism. The track 43 is located in position to engage with the rollers 42 at the place where 60 the can clamps discharge the cans from the

machine and said track has an inclined portion 44 that operates to swing the arms 41 of the can clamps in a direction to release the can clamps from the cans, said inclined part 44 merging into a part 45 which is 70 concentric with the axis of the carrier shaft, and with another inclined part 46 which operates to swing the arms 41 back into their original or clamping position. The inclined part 46 is located at a point 75 in the orbit of the rollers 42 where it will be engaged by the rollers after the cans have been delivered to the can clamps whereby the cans are clamped in place as 80 they start their passage through the machine. A feed chute 47 is provided at the receiving end of the machine, through which the cans, to be tested, are delivered to the can clamping heads. It will be understood that directly after each can is 85 clamped by a can clamping head, compressed air is admitted to the can and to an associated balancing tank, one for each can or associated pair of cans, and the air is thereupon trapped in said cans and balancing tank and held therein while the cans are carried around by the carrier to the discharge end of the machine, where communication is established between the cans, their 90 associated tank and the testing apparatus. 95 where the hermetically tight cans are selected and separated from the leaky cans, by discharging the leaky cans through one discharge passage and discharging the tight cans through a different passage. The means 100 for supplying the compressed air and controlling the same will now be described.

Referring to Figs. 1, 2, 3 and 4 a series of compressed air balancing tanks 50 will be seen mounted on the carrier 26, there being 105 one tank for each can clamping head. Compressed air is admitted simultaneously to a tank 50 and to the can or cans clamped to the associated can clamping head, said compressed air being supplied from a compressed air reservoir 51, here shown as contained in the body 21 of the machine and supplied with compressed air by any suitable air compressor. A compressed air pipe 52 leads from said compressed air reservoir 51 110 and delivers compressed air into a stationary tubular member 53 contained within the hollow of the shaft 23 and hub 26^a, and extending from the rear end thereof to the front of the mechanism as is clearly seen in Fig. 2. Into the other end of the tubular member 53 is screwed a fitting 54, from which leads a compressed air pipe 55 that discharges into the air chamber of an air valve device 56 (see Figs. 13, 14) from which 115 lead three compressed air pipes 57, 58, 59 that run to ports or perforations in a shoe 60 supported in a stationary disc like head 61 which is keyed or otherwise rigidly secured 120 to the tubular member 53. Between the 125 130

main air chamber of the air valve device 56 and the several compressed air pipes 57, 58, 59 which lead therefrom, are valves 62, 63, 64 (see Fig. 13) which are normally closed, but 5 which are arranged to be opened by the action of the cans themselves, directly after they have been clamped in place by the can clamping heads. As shown the valve actuating mechanism for the valves 62, 63, 64, 10 comprises arms 65, 65^a (see also Fig. 18) one for each of the pair of cans, carried by the carrier, which arms are mounted on rock shafts 65^b, 65^c, on which are other arms 66, 66^a which are connected to links 67, 67^a that 15 are connected to the valve actuating levers 68, 68^a by bell crank levers 69, 69^a, links 70, 70^a, the bell crank levers 71, 71^a and links 72, 72^a. The valve actuating levers 68, 68^a are mounted upon the casing or frame of the air 20 valve device 56 and have arms that are arranged to engage with the stems of the valves 62, 63, 64 to unseat said valves whenever the valve actuating levers 68, 68^a are actuated. Each lever 68 or 68^a is arranged 25 to unseat the middle valve (as seen in Fig. 13) and the end valve 62 or 64, associated with the lever. Each end valve 62 or 64 controls the compressed air conduit for one 30 can of each pair of cans, and when one of said valves is opened, compressed air is admitted to the can to which the compressed air conduit leads. In case a can clamping head passes the valve actuating levers 65, 65^a with only one can clamped in place, only one 35 lever 65 or 65^a will be actuated and consequently only one end valve 62 or 64 will be opened. The middle valve 63, however, will be opened, whenever either end valve 62 or 64 is opened, whereby compressed air will be 40 admitted to the can held by the can clamping head and to the balancing tank 50 associated with said head.

After the cans and associated balancing tanks have been filled with compressed air it 45 becomes necessary to trap the air in the cans and tanks while the cans are being carried around to the discharge end of the machine. The mechanism for controlling the compressed air, delivered from the valve device 56 to the cans and associated balancing tanks 50 will now be described.

The compressed air pipes 57, 58, 59 lead 55 to the shoe 60 as above described and said shoe bears against a ring 73 mounted on the carrier 26 and secured to it by an annular bracket 74 (see Figs. 2 and 3). In said ring 73 are formed ports 75, arranged in concentric rows in the ring 73 and arranged to be brought into register with the ports for the air pipes 57, 58, 59 that terminate in the shoe 60. Leading from said ports 75 are air pipes 57^a, 58^a, 59^a, one set for each balancing tank 50 and associated clamping head. The air pipes 57^a, 58^a, 59^a, form extensions to the 60 compressed air pipes 57, 58, 59 and lead to

a valve 150, one for each tank 50, from which tank lead pipe extensions 57^b, 58^b and 59^b that run to the can clamping heads and associated aid balancing tank. The valve 150 contains separate air passages for the associated air pipes 57^a, 57^b, 58^a, 58^b and 59^a, 59^b, whereby when the valve is opened, the compressed air may pass through the valve from one set of air pipes to the other set and thence to the cans and balancing tank associated therewith. Each pipe extension 57^b leads to and through a pad 29, and each pipe extension 59^b leads to and through a pad 29^a, while each pipe extension 58^b leads to the air balancing tank 50 associated with said pads. On the end of each valve stem 76 of the air valves 150, is a valve actuating arm 77, which is arranged to engage with a roller 78 mounted on a bracket 79, which is carried by the stationary head 61. The arrangement 75 is such that as the valves 150 move past the roller 78, the valve actuating arm 77 of each valve encounters the roller and is thereby partially rotated so as to close the passages 80 through the associated valve 150 thereby trapping the compressed air in the associated cans and balancing tank. At the discharge end of the machine is a roller 80 mounted upon a bracket 81, also secured to the stationary head 61 and said roller 80 is arranged to engage the valve actuating arms 77 and turn said arms back as they pass by said roller, thereby again opening the passages through the associated valve 150 and permitting the compressed air to escape from 90 the associated cans and balancing tank to the selectors. The valves 150 remain open after the cans have been tested and discharged from the carrier heads, and are again closed after other cans have been delivered to the same can clamping head as the one from which selected cans have been discharged.

The selectors, designated by the reference letters A, A¹, are mounted upon the stationary head 61 of the machine (see Fig. 15) and contain pneumatically operated mechanism which is arranged to be placed in communication with the cans and associated balancing tanks just prior to the time that 100 the cans are released from the can clamping heads and discharged from the machine. The selectors are similar in construction and a description of one of them will suffice for both.

Referring now to Figs. 7 to 12, inclusive, as shown, each selector is provided with a casing 82, having a supporting plate 82^a which is bolted or otherwise secured to the stationary head 61 of the machine and a glass door or cover 82^b. Mounted in the hollow of said casing are two bowed, tubular air gauge springs or tubes 83, 84 formed with very light gauge material, both closed at their free ends, and secured to and open-

ing at their other ends, into nipples 85, 86, which are supported by the casing 82 and are connected to a shoe 87 (see also Fig. 15) mounted on the stationary head 61 of the machine and held in pressing contact with the perforated ring 73. The air gauge tube 83 and nipple 85 of each selector communicate with the middle port of the shoe 87 by an air pipe 88 and its branches, as seen in Fig. 15, and through said port and the middle row of ports of the ring 73 said air gauge tube communicates with a balancing tank 50 during the interval in which a port of the middle row of ports in the ring 73, passes the middle port of the shoe 87. The air gauge tube 84 and nipple 86 of one selector connects with a port in the shoe 87 through an air pipe 89 and the air gauge tube 84 and nipple 86 of the other selector connects with another port in the shoe 87 by an air pipe 90. The port in the shoe 87 for the air pipe 89 of selector A, is arranged to come into register with the ports 75 of the air pipes 57 that run to the valves 150 and from which lead the pipes 57^b that run to the pads 29 of the can clamping heads (see Fig. 3) and the port for the air pipe 90 of selector A¹, is arranged to come into register with the port of the air pipes 59^a that run to the valves 150, from which lead the pipes 59^b that run to the pads 29^a of the same can clamping heads. The arrangement of the ports and air pipes is such that whenever any three aligned ports in the ring 73 come into register with the three ports in the shoe 87, communication is established between a balancing tank 50 and the air gauge tubes 84 of the selectors, the air conduit for one can being opened to the tube 84 of the selector A, and the conduit for the other can being opened to the tube 84 of the other selector A¹. When compressed air is admitted to the companion air gauge tubes 83, 84, they tend to expand or straighten out under the influence of the compressed air, and if the pressure in both air gauge tubes is equal the two tubes expand or straighten out equally or to the same degree. However, if the pressure has fallen in one of the cans, the air gauge tube communicating therewith will expand or straighten out less than its companion air gauge tube, whereby mechanism is set in motion which causes the leaky cans to be discharged from the machine into a different place than the hermetically tight ones.

Rotatively mounted in a bearing bracket 91 contained in the casing 82 is an arbor 92 which is preferably provided with ball bearing or other anti-friction bearings whereby the arbor may rotate freely, and secured upon one end of said arbor is a crank arm 93, one end of which is connected to the closed ends of both air gauge tubes 83, 84 by links 95, which are preferably made ad-

justable lengthwise of each other to afford a close adjustment between the crank arm 93 and the closed ends of the air gauge tubes 83, 84. Secured upon the other end of the arbor 92 is an arm 96 which is preferably counterbalanced at its upper end and movable between two stop pins 97 which are secured in the front wall 98 of the casing 82. Normally the arm 96 stands in a neutral position as indicated in Figs. 7 and 8, but whenever the arbor 92 is turned upon the axis (which occurs when there is an unequal expansion or straightening out of the companion air gauge tubes 83, 84) then the arm 96 is moved out of its neutral position and becomes effective for the purpose of separating out a defective can.

In the form of the invention illustrated, the lower end of the arm 96 is provided with an enlargement of thickened portion 99, which is interposed between two reciprocal motion transferring members 100, 101 which are slidably mounted in the body of the casing 82. A notch 102 is formed in the member 100 which notch is in alignment with the arm 96 and its enlargement 99 whereby said member 100 may be reciprocated independently of the member 101 so long as the arm 96 remains in alignment with the notch 102. In case the arm 96 is moved out of alignment with the notch it becomes interposed between the solid portions of said members 100, 101 whereby whenever the member 100 is moved in a direction toward the arm 96, the member 101 will be correspondingly moved because of the interposed part of the arm 96, and said endwise movement of said member 101 is used for transmitting motion so as to deflect a certain track or run way for the discharge of the cans, whereby a defective can is discharged through a different discharge track or run way than the perfect can. In the form of motion transmitting members 110, 101 shown, the member 100 has a plate 103 on its forward end which contains the notch 102 and the member 101 has a plate 104 secured to its adjacent end, which lies behind the plate 103. Coiled compression springs 105 contained between shoulders on the members 100, 101 and the bottoms of recesses formed in the body of the case 82, serve to yieldingly hold the members 100, 101 in the position shown in Fig. 8 of the drawing.

Journaled in suitable bearings mounted on the frame work of the machine is a cam shaft 106 (see Figs. 1 and 5) which is driven to make one complete revolution for the purpose of selecting the cans of each can clamping head, and on one end of said cam shaft 106 is a cam block 107 which contains a cam that is arranged to engage with a roller 108 on a lever 109, once during each revolution of the cam block to thereby swing back said lever 109 on its fulcrum. To one arm of

said lever 109 is connected a link 110, the other end of which connects with levers 111, 112 which are pinned or otherwise secured upon short rock shafts 113 that are journaled 5 in bosses formed on the cases 82 of the two selectors. On the inner end of each rock shaft 113 is secured a crank arm 114 which is provided with a pin or lug 115 that engages with a forked portion 116 of the motion 10 transmitting member 100. The arrangement of the parts is such that whenever the cam of the cam block 107 swings back the lever 109, it draws down the link 110, swings both levers 111 and 112, thereby 15 rocking the shafts 113 of each selector and therewith the crank arms 114 thereof, which in turn move the member 100 in the direction of the arrow thereon in Fig. 8. If the cans or cans are sound, which are in communication 20 with the selectors at the time the member 100 is moved, the arm 96 remains in neutral position thereby permitting the notched plate 103 to pass the arm 96 and without affecting the member 101. If, however, 25 the pressure in either or both of said cans has become lowered and the arm 96 of the selector for said unsound can is to be swung out of its neutral position, the notched plate 103 engages the enlargement 30 of the arm 96 and through it moves the member 101 in the direction of the arrow in Fig. 8, which has the effect of setting into action certain can separating mechanism as will be presently described. For the purpose 35 of adjustably locating the normal stationary position of the motion transmitting members 100, 101, with respect to the arm 96, adjustment screws 145, 146, are provided which form stops against which the crank 40 arms strike when the members 100, 101, reach their proper normal stationary position with the arm 96 between them.

Journaled in a boss upon the side of each casing 82 opposite the rock shaft 113, is a rock shaft 117 which has a crank arm 118 upon its inner end that engages with a forked part 119 of the member 101. Upon the outer end of said rock shaft 117 is an arm 120 which is connected to a link 121 that runs to a crank arm 122. It will be understood that the crank arm 120 of each selector is connected to a separate link 121 and that each link 121 is connected to a separate arm 122. One of the arms 122 is mounted upon a rock shaft 123 (see Figs. 5 and 6) journaled in the frame work of the machine and the other arm 122 is mounted upon a sleeve 124 surrounding said shaft 123. Secured 55 upon the sleeve 124 is a detent setting member 125, and secured upon the rock shaft 123 is a similar detent setting member 126, each of which members are held in retracted positions by a coiled tension spring 127 as seen in Fig. 5.

Rotatively mounted on stud shafts 128 se- 60 cured in the framework of the machine are two trap door operating levers 129, 130. Said levers 129, 130 are arranged to be actuated by cam blocks 131 rigidly mounted on the shaft 106. Rotatively mounted on the same stud shafts 128 are levers 132, which are provided with spring actuated detents 133 that are adapted to engage in notches 134, formed in the levers 129, 130, whenever the associated detent setting arm 125 is actuated. The arrangement is such that the cams 131 may rotate and oscillate the trap door actuating levers 129, 130 without affecting the levers 132, but whenever the detent 133 of either lever 129, 130 is swung into the notch 134 then the two levers 129 or 130 and 132 become rigidly connected together so that the movement imparted to the lever 129 or 130 by a cam block 131 is transmitted to an associated lever 132 and the far end of 65 said lever is depressed, thereby swinging up a trap door for discharging a defective can.

At the discharge end of the machine is a discharge chute 135 in which are track ways 136, one track way for each row of cans contained on the carrier. The forward portions 136^a of said track ways are movable and form trap doors that are mounted upon rock shafts 137, 137^a, and said rock shafts 137, 137^a have arms 138, 138^a secured thereto, which arms are connected to the levers 132 by links 139. Coiled tension springs 139^a connect the levers 132 with some stationary portion of the frame work and act to swing said levers upward and therewith hold the trap doors 136^a in the position indicated in Fig. 5 wherein the solid or perfect cans may roll down when discharged from the carrier head and be delivered in a suitable receptacle or otherwise disposed of. Below the tracks 136, 136^a 70 are other tracks 136^b upon which the imperfect cans are discharged, it being understood that when an imperfect can or cans reach a position where it would otherwise be discharged upon the trap door or doors 136^a that such track portions are swung upward by the track door actuating means described, far enough to permit the imperfect can or cans to fall upon the lower track ways 136^b, from which they are discharged into some 75 other receptacle, rack, or receiver.

Can ejectors 140 (see Fig. 1) may be employed at the discharge end of the machine for ejecting the tested cans from the can clamps. Said can ejectors are in the form 80 of L shaped arms, the bent ends of which lie in the paths of movement of the cans, and said ejectors are fulcrumed upon the frame of the machine and connected to a lever 141 by a link 142 (see Fig. 5). A cam block 143 85 on the shaft 106, and substantially like the cam 107, is arranged to engage a roller on said lever 141 in timed relation to the instant of discharge of the cans, and swings down said lever 141, thereby drawing down 90

on the link 142 and swinging down the ejectors upon the cans and ejecting them from the carrier.

In the operation of the machine, the carrier is rotated in the direction of the arrow in Fig. 1 and compressed air is supplied to the compressed air chamber of the air valve device 56. When the construction shown is used, compressed air is supplied to the reservoir 51 and piped to the air valve device 56 as heretofore described. The cans to be tested are placed in the chute 47 with the open ends thereof in position to engage with the pads 29, 29^a of the can clamping heads. The cans roll down the chute and enter the can carriers and directly thereafter the roller 42 of the can clamping mechanism rides up the inclined part 46 of the track or guide way 43 and draws the links 38, 39 past an imaginary line extending through the pivot points of the links and pivot point of the lever 40 thereby locking the links in clamping position. The clamping discs connected to said links thereby clamp the cans against the pads 29, 29^a. As the cans proceed they encounter the valve actuating arms 65 and open the valves 62, 63, 64 of the air valve device 56. The air valve 150 has been opened before this time and at the time the valves 62, 63, 64 are opened, the ports 75 of the air pipes 57^a, 58^a, 59^a, in the ring 73 register with the ports in the shoe 60 for the air pipes 57, 58, 59, and compressed air flows through the air pipes 57, 58, 59, shoes 60, 73, air pipes 57^a, 58^a, 59^a, valve 150, through pipes 57^b, 59^b and into the cans, and through pipe 58^b and into the associated air balancing tank 50. Immediately thereafter the arm 77 of the air valve 150 counters the roller 78, which turns the arm and therewith closes the valve 150, thereby trapping the compressed air in the two cans and associated tank 50. The pressure in both cans and associated tank 50 is therefore equal at the start. The same sequence of operations take place with other cans that are delivered to the can clamping heads, except that if a can fails to enter any head the arm 65 for that side of the carrier is not actuated by a can and consequently the end valve 62 or 64 for the empty part of the can clamping head remains closed.

The carrier carries the cans around to the discharge end of the machine, which is close to the receiving end and as the ports 75 for the air pipes 57^a, 58^a, 59^a begin to register with the ports in the shoe 87 for the air pipes 88, 89, 90 that lead to the air gauge tubes 83, 84 of the two selectors A, A¹, the arm 77 of the air valve 150 engages the roller 80 and is turned back, thereby opening the valve 150 and permitting the air under pressure from the two cans and associated tank 50 to enter the air gauge tubes 83, 84, causing them to expand or straighten out. If at

this time the pressure in the cans and associated tank 50 remains equal, the air gauge tubes 83, 84, will expand equally and the arm 96 will be left in neutral position. If, however, the pressure in either can is lowered, due to a leaky can or otherwise, the air gauge tubes will expand unequally, the crank arm 93 will be partially rotated, and the arm 96 turned slightly, thereby bringing its end out of alignment with the notch in the member 100 and interposing said end between the solid parts of said members 100, 101.

At the instant the arm is so interposed between the solid parts of the members 100, 101, the cam on the cam block 107 encounters the lever 109, swings it down, thereby drawing the link 110 down and moving motion transmitting members 100 toward the members 101, through the instrumentality of the link 110, levers 112, rock shafts 113, and crank arms 114. In the selector or selectors where the arm 96 remains neutral, the member 100 is moved idly, but in case pressure in one of the cans has lowered, the arm is swung over between the solid parts of the members 100, 101, and the member 101 is thereby moved endwise by the member 100. Motion is thereby transmitted from the member 101 to the arm 122 (see Fig. 5) by the crank arm 118, rock shaft 117, lever 120, and link 121, and the sleeve or rock shaft 123 or 124 connected to such arm 122 is turned thereby, forcing the detent setting arm 125 against the detent 133, and moving said detent into the notch of the lever 129 or 130 as the case may be, at which time the cam or the cam block 131 encounters the lever 129 or 130, moves it upward, thereby moving down the lever 132, and moving upward the trap door 136^a through the instrumentality of the link 139, arm 138, or 138^a and rock shaft 137 or 137^a to which the trap door is secured. The imperfect can therefore drops upon the track way 136^b and is discharged through one passage, and the sound can falls upon the unraised trap door and is discharged through another passage. As the cans arrive at the discharge place, the ejectors 140 engage the cans and eject them from the can carrier. It will be observed that after the cans have been tested by the selectors, the rollers 42 of the can clamping head encounter the inclined part 44 of the guide way 43 and move back the can clamping discs, thereby releasing the cans, whereby they are free to discharge from the carrier.

From the above it will be seen that compressed air is admitted to each balancing tank and the cans associated therewith, at the receiving end of the machine, held in the tank and cans for a predetermined length of time, to permit air to escape from a leaky can and thereby lower the pressure therein,

and thereafter the air from each tank and associated can or cans is exhausted into the selector associated with each circumferential row of cans. In a can tester in which only one can is held in each can clamping head only one selector is needed, but where two or more cans are held by each can clamping head, a selector is required for each circumferential row of cans in order to test the cans of the separate rows and separate out the tight cans from the leaky ones.

It will be understood that the selector or selectors must be adjusted carefully to operate with cans of a given capacity and that when cans of a different capacity are to be tested the selectors must be adjusted correspondingly. Furthermore, because of the difference in length of the air conduits leading from the balancing tanks to the selectors and those leading from the cans to the selectors, the selectors must be adjusted to compensate for any slight difference in pressure produced in the opposed air gauge springs when the air is exhausted from the balancing tanks and cans into the selectors. While the pressure which is put into the tanks and cans may be equal, when returned to the selector, the pressure in one air gauge spring may be slightly lower than that in the other air gauge spring, and must be compensated for so that the arm 96, which is interposed between the moving element 100 and the element 101 moved thereby, may stand behind the notch 102 to render the element 101 inactive if the can being tested is light, despite the fact that the pressure in the two air gauge springs is not precisely equal. The arm 96 is therefore adjustably secured upon the arbor 92 as for instance by a clamp member 96^x (see Figs. 7 and 8) and clamp screws 96^z. The adjustment is made by using a known tight can and when the air gauge springs are extended from the pressure received from a balancing tank and the tight can, adjusting the arm 96 to stand in a neutral position behind the notch 102, and tightening up the clamp to lock the arm 96 on the arbor 92. Obviously the arm may be out of register with the notch when the air gauge springs are relaxed, but whenever the air pressure from the tanks and associated tight cans is exhausted into the air gauge springs, the arm is moved into neutral position behind the notch.

While the machine has been shown and described with can clamping heads and pads for holding two cans in each head, the heads may be made to hold one or more cans, and the number of selectors made to correspond with the number of cans carried by any one head. With this construction shown only one selector is required for each circumferential row of cans thereby greatly simplifying the construction and cost of the machine.

While the selectors are shown and described as employing opposing air gauge springs for actuating the arm 96, other equivalent pneumatically operated mechanism may be substituted wherein opposed pressures are employed for moving the pneumatically operated device.

It will be observed that although the pressure in the supply reservoir may vary considerably during a day's run, the selectors will operate with equal delicacy and certainty regardless of such variation in pressure. Moreover, the mechanism is entirely automatic in operation and requires only the usual attention given to mechanical oppositions of like character.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. In a can testing machine, a pneumatically operated selector comprising a pair of balanced air gauge springs arranged to be connected respectively to a can to be tested and to an associated air balancing tank, motion transmitting means for transmitting motion from a prime mover to a can separating mechanism, and normally inactive means, operated by said air gauge springs under the influence of differential pressure therein, and forming an operative connection in said motion transmitting means.

2. In a can testing machine, a pneumatically operated selector comprising a pair of balanced air gauge springs, adapted to be connected respectively with a can to be tested and an associated air balancing tank, a primary, motion transmitting element and an associated, normally inactive, motion transmitting element for transmitting motion to a can separating mechanism, an interposed member between said motion transmitting elements, normally occupying an inactive position, and connecting means between said pair of air gauge springs and interposed member, operating under the influence of differential pressure in said springs, to move said interposed member into an active position whereby motion is transmitted from said primary power transmitting element to said normally inactive motion transmitting element.

3. In a can testing machine, a selector comprising a pair of oppositely disposed air gauge springs stationarily mounted at one end, and said end of one spring being adapted to communicate with a can to be tested and said end of the other spring being adapted to communicate with an associated

air balancing tank, a continuously operating motion transmitting element and a normally inactive motion transmitting element for transmitting motion to a can selecting mechanism, an interposed member between said motion transmitting elements, normally occupying an inactive position, and operative connections between the free ends of said bowed air gauge springs and said interposed member.

4. In a can testing machine, a selector comprising a pair of bowed air gauge springs, one end of both of which is stationarily supported, one spring being adapted to communicate with a can to be tested and the other adapted to communicate with an associated air balancing tank, an arbor, a crank thereon, links connecting the free end of said air gauge springs with said crank, a continuously operating motion transmitting element and a normally inactive motion transmitting element, for transmitting motion to a can separating mechanism, and an interposed member mounted on said arbor and normally occupying an inactive position between said motion transmitting elements, but movable into an active position under the influence of differential pressure in said air gauge springs.

5. In a can testing machine, the combination of a pneumatically operated selector having a pair of bowed air gauge springs, one adapted to communicate with a can to be tested and the other adapted to communicate with an associated air balancing tank, motion transmitting elements, and an interposed member operated by said air gauge springs and movable under the influence of a differential pressure in said air gauge springs, from an inactive to an active position between said motion transmitting elements, means for actuating one of said motion transmitting elements, and trap door-can-discharge mechanism capable of being operated by the other motion transmitting element.

6. In a can testing machine, a pneumatically operated selector comprising a pair of balanced air gauge springs arranged to be connected respectively to a can to be tested and to an associated air balancing tank, a reciprocating motion transmitting element, a normally inactive motion transmitting element, one of said elements having a notch therein, and an interposed member between said motion transmitting elements, normally located in line with said notch, and operative connections between said air gauge springs and interposed member.

7. In a can testing machine, a selector comprising a pair of bowed air gauge springs, one end of both of which is stationarily supported, one spring being adapted to communicate with a can to be tested and the other adapted to communicate with an asso-

ciated air balancing tank, an arbor, a crank thereon, links connecting the free end of said air gauge springs with said crank, a continuously operating motion transmitting element and a normally inactive motion transmitting element, for transmitting motion to a can separating mechanism, one of said motion transmitting elements having a notch therein and an interposed member mounted on said arbor and normally occupying a position in line with said notch, and movable into an active position under the influence of differential pressure in said air gauge springs.

8. In a can testing machine, the combination of a carrier having a multiplicity of can sealing pads and associated can clamping heads thereon, balancing tanks, one for each head, mounted on said carrier, means for admitting fluid, under pressure, to a can held by a can clamping head and to an associated balancing tank, means for trapping said fluid in said can and tank, can selecting and separating mechanism including a pneumatically operated selector, and means for establishing communication simultaneously between said can and selector and said balancing tank and selector.

9. In a can testing machine, the combination of a carrier, having a multiplicity of can sealing pads and associated can clamping heads mounted thereon, balancing tanks, one for each head, mounted on said carrier, means for admitting compressed air to a can held by a can clamping head and to an associated balancing tank, including air control means actuated by the cans, means for trapping compressed air in said can and balancing tank, can selecting and separating mechanism, including a pneumatically operated selector, and means for establishing communication between said can and selector, and said tank and selector.

10. In a can testing machine, the combination of a carrier having a multiplicity of can sealing pads and associated can clamping heads mounted thereon, air balancing tanks, one for each head, mounted on said carrier, means for admitting compressed air to a can held by a can clamping head and to an associated air balancing tank, means for trapping said compressed air in said can and tank; a selector having two bowed gauge springs, normally inoperative motion transmitting means, and an interposed element operated by the bowed gauge springs; means for admitting air from a can to one of said bowed gauge springs and from an associated tank to the other bowed gauge spring, and can separating mechanism controlled by a member of said motion transmitting means.

11. In a can testing machine, the combination of a rotatory carrier having a multiplicity of can sealing pads and associated

- can clamping heads arranged circumferentially about said carrier and mounted thereon, air balancing tanks, one associated with each can clamping head, a source of compressed air supply, means for admitting compressed air from said supply simultaneously to a can held by a can clamping head and to an associated air balancing tank, means for trapping compressed air in said can and associated air balancing tank, can selecting and separating mechanism including a pneumatically operated selector, and means for establishing communication between said can and selector and said air balancing tank and selector. 5
12. In a can testing machine the combination of a rotatory carrier having a multiplicity of can sealing pads and associated can clamping heads arranged circumferentially about said carrier and mounted thereon, air balancing tanks, one associated with each can clamping head and mounted on said carrier, a source of compressed air supply, individual compressed air conduits for said cans and associated air balancing tanks arranged to communicate with said source of compressed air supply, air valve devices interposed in said conduits, means arranged to close said valve devices and thereby trap compressed air in said cans and associated air balancing tanks, can selecting and separating mechanism, including a selector having two balanced air gauge springs and motion transmitting means controlled thereby, air conduits leading from said air gauge springs, and arranged to communicate with said individual compressed air conduits, and means for opening said air valve devices, when the said individual compressed air conduits are in communication with said air gauge spring conduits. 10
13. In a can testing machine, the combination of a rotatory carrier having mounted thereon a multiplicity of circumferentially arranged can sealing pads and associated can clamping heads, air balancing tanks, one for each can clamping head, a source of compressed air supply, compressed air conduits for simultaneously conducting compressed air to cans held by said can clamping heads and associated air balancing tanks, air valves interposed in said conduits, means for closing said valves at the receiving end of the machine and for opening said valves at the discharge end of the machine, can selecting and separating mechanism, including a pneumatically operated selector, operable under a differential pressure in a can and associated air balancing tank, to separate leaky cans from tight ones, and conduits for establishing communication between said compressed air conduits of the cans and air balancing tanks and selector while said valves are open. 15
14. In a can testing machine, the combination of a rotatory carrier having circumferentially arranged can sealing pads and can clamping heads thereon, air balancing tanks, one for each can clamping head mounted on said carrier, a source of compressed air supply and compressed air conduits leading from said source of compressed air supply, one conduit being for the cans to be tested and one for the balancing tanks, valves controlling said conduits, a lever lying in the path of movement of the cans and actuated by said cans and operative connections between said lever and valves for opening said valves and thereby permitting compressed air to pass to the cans, a stationarily mounted selector, and means for establishing communication simultaneously between said selector and a moving can and associated air balancing tank. 20
15. In a can testing machine, the combination of a rotary can carrier having circumferentially arranged can sealing pads and can clamping heads mounted thereon, air balancing tanks, one associated with each can clamping head, means for supplying compressed air simultaneously to a can clamped in said clamping head and to an associated air balancing tank, a stationarily mounted selector, and means for establishing communication simultaneously between said selector and a moving can and associated air balancing tank, said selector including a primary motion transmitting element and a normally inactive motion transmitting element actuated thereby. 25
16. In a can testing machine, the combination of a continuously rotating cam shaft, cams mounted thereon, a lever actuated by one of said cams and a trap door actuating lever actuated by another of said cams, a pneumatically operated selector having motion transmitting elements, each connected to one of said levers, the trap door actuating lever having a normally inactive arm connected to the trap door, and setting mechanism actuated by the first mentioned lever for setting said trap door actuating lever into operative position. 30
17. In a can testing machine, a selector, a primary motion transmitting element and a normally inactive motion transmitting element, a pair of air gauge springs adapted to communicate with a can to be tested and an associated air balancing tank, means operated by said air gauge springs for operatively connecting said elements, a rock shaft and means for rocking said rock shaft, a crank arm on said rock shaft engaging with said primary motion transmitting element, a crank arm engaging with said normally inactive motion transmitting element, a rock shaft on which said last mentioned crank arm is mounted and can separating mechanism operatively connected to said last mentioned rock shaft. 35

18. In a can testing machine, a selector comprising a pair of bowed oppositely disposed air gauge springs one adapted to be connected to a can which is to be tested and the other adapted to be connected to an associated air balancing tank, an arm connected to and operated by said air gauge springs, a reciprocatory motion transmitting element, a normally inactive reciprocatory motion transmitting element, one of said elements having a notch with which said arm is normally aligned whereby the primary motion transmitting element may reciprocate idly except when said arm is moved out of normal position, a continuously rotating shaft and operative connections between said shaft and primary motion transmitting element for continuously reciprocating said element, a trap door for separating leaky cans from tight ones and operative connection between said trap door and said second mentioned motion transmitting element.

19. In a can testing machine the combination of a carrier having a multiplicity of can sealing pads and associated duplex can clamping heads thereon for clamping two rows of cans in the heads, air balancing tanks, one for each two cans held in each head, means for admitting compressed air to each can held by said heads and simultaneously to an associated air balancing tank, means for trapping compressed air in said cans and associated tanks, can selecting and separating mechanism for each row of cans, including a pneumatically operated selector for each row of cans, and means for separately establishing communication between the cans of one row and their associated air balancing tanks with one selector, and between the cans of the other row and their associated air balancing tanks and the other selector.

20. In a can testing machine, a can clamping head having a stationary clamping member, a can sealing pad thereon, oppositely disposed, can clamping discs arranged to clamp two cans upon said stationary clamping member, one of said discs having a can sealing pad thereon, clamping arms supporting said discs, and arm actuating means for operating said discs, there being compressed air conduits leading from said can sealing pads to a source of compressed air supply.

21. In a can testing machine having a receiving end and a discharge end, the combination of a rotary carrier having mounted thereon a multiplicity of circumferentially arranged can clamping heads and air balancing tanks, one tank for each head, means for admitting compressed air, at a place adjacent the receiving end of the machine, to each can and its associated balancing tank, means for holding the compressed air in the cans and associated balancing tanks for a predetermined length of time, a stationary

selector, operated by two opposed pressures, and located adjacent the discharge end of the machine, and means for exhausting the air from each can and its associated balancing tank into said selector.

22. In a can testing machine having a receiving end and a discharge end, the combination of a rotary carrier having mounted thereon a multiplicity of circumferentially arranged can clamping heads, each head arranged to hold a group of cans, air balancing tanks mounted on said carrier, one tank for each head, means for admitting compressed air, at a place adjacent the receiving end of the machine, to each can and its associated balancing tank, means for holding the compressed air in the cans and associated balancing tanks for a predetermined length of time, stationary selectors located adjacent the discharge end of the machine, there being as many selectors as cans in the group held by any one can clamping head, and means for exhausting the air from each balancing tank and separately from the several cans associated with each tank into associated selectors.

23. In a can testing machine, the combination of a rotary carrier having a multiplicity of circumferentially arranged can clamping heads and balancing tanks thereon, one tank associated with each head, means for admitting fluid under pressure, at a predetermined place, to a can held by each head, and to an associated balancing tank, means for holding the fluid in said cans and associated tanks for a predetermined length of time, and a stationary selector, having actuating means operated by two opposing pressures, and means located at a predetermined place for exhausting the fluid from each can and its associated balancing tank into said selector.

24. In a can testing machine, the combination of a rotary carrier having a multiplicity of circumferentially arranged can clamping heads thereon, each head capable of holding several cans, balancing tanks, one for each head, means for admitting compressed air, at a predetermined place, to cans held by each can clamping head and to its associated balancing tank, means for holding the air in said cans and tanks for a predetermined length of time, and can selecting and separating mechanism including several pneumatically operated selectors and means adjacent the discharge end of the machine for establishing communication between the selectors and the balancing tanks and their associated cans, there being as many selectors as there are cans held by any one clamping head.

25. In a can testing machine, a pneumatically operated selector comprising a pair of opposed air gauge springs, air conduits connected thereto and arranged to communicate

respectively with a can to be tested and with an air balancing tank, a swinging actuating member, operatively connected to both of said air gauge springs and capable of being moved thereby from a normal inoperative position to an operative position, and adjustment means for varying the normal position of said actuating member.

26. In a can testing machine, a pneumatically operated selector comprising a pair of opposed air gauge springs, air conduits connected thereto and arranged to communicate respectively with a can to be tested and with an air balancing tank, a rock shaft operatively connected with said air gauge springs and receiving motion therefrom, a swinging actuating member mounted on said rock shaft, and capable of being moved thereby from a normal inoperative position to an operative position, and adjustment means for varying the normal position of said actuating member on said rock shaft.

27. In a can testing machine a stationary selector having actuating means operated by two opposing pressures, a carrier for carrying cans, containing compressed air, past said selector, means carried by said carrier, for containing compressed air of substantially the same pressure as in the cans, and means for exhausting the pressure from the cans and compressed air containing means into the selector.

28. In a can testing machine, a carrier having can clamping heads mounted thereon for carrying cans containing compressed air, and having balancing tanks containing compressed air of substantially the same pressure as that in the cans, a selector having means operated by two opposed pressures, said selector being separate and distinct from said means, and controlled means for exhausting the air from said cans and tanks into said selector.

CHARLES D. McDONALD.
